(57) **CLAIM**

We claim the ornamental design for a leg rigging clip, as shown and described.

DESCRIPTION

FIG. 1 is a perspective view of a leg rigging clip in accordance with a first embodiment of our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a right side elevational view thereof;

FIG. 8 is a perspective view of a leg rigging clip in accordance with a second embodiment of our new design;

FIG. 9 is a top plan view thereof;

FIG. 10 is a front elevational view thereof;

FIG. 11 is a rear elevational view thereof;

FIG. 12 is a bottom plan view thereof;

FIG. 13 is a right side elevational view thereof; and,

FIG. 14 is a left side elevational view thereof.

The broken lines depict unclaimed environmental subject matter and form no part of the claim.
